(57)

CLAIM

The ornamental design for a soap dish, as shown and described.

DESCRIPTION

FIG. 1 is a perspective view showing a new design for a soap dish;

FIG. 2 is a front elevation view thereof;

FIG. 3 is a rear elevation view thereof;

FIG. 4 is a right side elevation view thereof, a left side elevation view being a mirror image thereof;

FIG. 5 is a top plan view thereof; and,

FIG. 6 is a bottom plan view thereof.
